(57) **CLAIM**

The ornamental design for a light source module, as shown and described.

DESCRIPTION

FIG. 1 is a front, bottom and right side perspective view of a light source module, showing an initial embodiment of our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged detail view of the portion of the claimed design shown in the dashed box in FIG. 1 thereof;
FIG. 9 is an enlarged detail view of the portion of the claimed design shown in the dashed box in FIG. 2 thereof;
FIG. 10 is a partially sectional view of FIG. 7, taken along line 10-10 of FIG. 9 thereof; and,

FIG. 11 is a partially sectional view of FIG. 7, taken along line 11-11 of FIG. 9 thereof.

The solid line expresses the other portion for the part for which design registration is sought with the dashed line as a partial design. Dotted and dashed lines represent boundaries between the portions intended for registration as a partial design and the other portions.
